FUEL VALVE AND NOZZLE CLEANING MECHANISM FOR PORTABLE LIQUID FUEL BURNERS

Carl Bramming, Anderson, Ind., assignor to Aladdin Industries, Incorporated, a corporation of Illinois

Application June 5, 1944, Serial No. 538,748

8 Claims. (Cl. 158—120)

1

The invention pertains to an improved construction of portable stove for burning liquid fuel, intended for use as a part of traveling or portable kits for soldiers, sportsmen, explorers and the like, as a result of which the size and weight of the stove must be kept as small as possible to facilitate its ready portability.

This invention is an improvement on my portable stove construction disclosed in U. S. patent application Serial No. 483,107, filed April 15, 1943, now Patent No. 2,465,572 issued March 29, 1949.

The object of the present invention is to simplify the construction and operation of the fuel valve mechanism heretofore proposed for portable stoves, and at the same time provide independent mechanism for cleaning the fuel nozzle of the stove when and as desired, without in any way increasing the size or weight of the stove over that required for the earlier construction thereof, the object being to reduce both the size and weight of the stove from said earlier construction, to the end that the stove may be more conveniently used for its intended purposes.

The stove disclosed is intended for operation with liquid fuel, for example gasoline, and the devices requisite for the proper burning of the fuel are incorporated in the stove, namely, a fuel valve to control the flow of the fuel from a reservoir to the burner, a generator for vaporizing the fuel, a burner housing, a fuel nozzle for delivering vaporized fuel into the burner housing, and collapsible pan supports on the casing of the stove. In addition to the structure referred to, the present construction includes nozzle cleaning mechanism having operating devices independent of the fuel valve mechanism, by which the discharge opening in the fuel nozzle may be cleaned when and as desired, without in any way interfering with the adjustment at the time of the fuel valve.

With portable stoves of the kind described, in view of the importance of maintaining the size and weight of the stove as small as can be done consistently with satisfactory operation of the stove, it is important to maintain all of the dimensions as small as possible without interfering with efficient operation. At the same time, the fuel reservoir of the stove must be of adequate size to contain sufficient fuel to maintain the operation of the stove for an appreciable time interval, to avoid the requirement of frequently replenishing the fuel supply. An important consideration with portable stoves is providing adequate valve and generator mechanism, without producing a stove structure of undesirably large height. To produce an efficient and compact construction, the fuel valve mechanism is placed directly above the reservoir, the generator is located immediately above the valve mechanism, and the burner is located immediately above the

2

generator, with the result that the structure is simple and at the same time effective. Experience has demonstrated that the generator must have an appreciable height in order to effectively vaporize the fuel, and that the burner housing must have a suitable height permitting the proper burning of the vaporized fuel in order to effectively utilize the heat of the burning fuel. In the present invention the fuel valve mechanism is of a simple form involving a single valve operated by a radially extending valve stem so that turning the valve stem opens and closes the valve. This permits making the valve housing short vertically, and it facilitates extending the lower end of the housing directly into the fuel reservoir, and supporting the generator directly on the upper end of the valve housing. The nozzle cleaning mechanism of the invention is operated by devices mounted in the valve housing itself, and to one side of the vertical axis of the valve housing, the said housing being provided with a radial extension angularly spaced from the valve stem, which extension supports a vertically movable arm for operating the nozzle cleaning devices, the supports of the movable arm and the valve stem being located in substantially the same horizontal plane. Connection is effected between the movable arm and the cleaning rod extending vertically to the nozzle, by means of a sliding block mounted in a vertical slot in the valve housing to one side of the fuel passage in the valve housing, and above said fuel passage said block is provided with an offset arm extending to the central portion of the valve housing to engage and support the cleaning rod substantially in the axis of the valve housing, the connection between the cleaning rod and the operating block being in the portion of the valve housing involved in connecting the generator of the stove with the valve housing, as a result of which the structure employed to support and operate the cleaning rod does not require any increase whatever in the over-all vertical dimension of the valve housing. The cleaning rod referred to extends upwardly through the generator and is provided with a cleaning needle at its upper end for entry into the nozzle aperture as a result of moving the operating arm referred to, so that the nozzle aperture may be cleaned when and as desired without moving the valve stem from the position it may then have.

The invention will be best understood by reference to the accompanying drawings illustrating a preferred embodiment thereof in which:

55 Fig. 1 illustrates the stove of the invention in vertical, central, sectional view,

Fig. 2 is a horizontal, sectional view of the valve construction shown in Fig. 1 taken along the line 2—2 in Fig. 1,

60 Fig. 3 is a vertical, sectional view through the

structure shown in Fig. 2 taken along the line 3—3 in Fig. 2, and

Fig. 4 is a horizontal, sectional view of the structure shown in Fig. 3 taken along the line 4—4 in Fig. 3.

Similar numerals refer to similar parts throughout the several views.

As shown in Fig. 1, the stove consists of a reservoir 10 which may be of convenient size and shape for the purpose described, having an internally threaded collar 11 secured in the central portion of its upper wall, into which the lower end of the valve housing 12 is tightly screwed. The upper end of the housing 12 is recessed to receive a connecting and packing ring 13 on which the lower end of the generator 14 is seated, an internally threaded ring 15 being provided engaging external threads on the upper end of the housing 12 to tightly clamp the lower end of the generator 14 against the ring 13 and in turn to tightly clamp the ring 13 against the upper end of the housing 12. The upper end of the generator 14 is internally threaded to engage corresponding external threads on the nozzle 16, and is also externally threaded at its upper end to engage and support a threaded ring 17 which in turn supports a burner housing 18. The nozzle 16 is provided with a discharge aperture 16a by which vaporized fuel is delivered into the burner housing 18, and the generator 14 contains screen material 14a to aid in breaking up and vaporizing the fuel so that the generator 14 may have a minimum vertical height to accomplish its intended purpose. The burner housing 18 comprises inner and outer portions 18a and 18b of similar form and angularly movable relatively to each other to regulate the effective size of openings 19a and 19b, so that the proper amount of air may be admitted to the burner housing to burn the vapor delivered into the same by the nozzle 16. The burner housing supports a baffle 20 over the nozzle 16 to spread the flame in the burner so that it may be distributed to the underside of the article being heated, which may be a pan or the like supported by the pan supports 21 of the stove, which pan supports are pivotally mounted at 22 on a ring extending around the upper end of the casing 23 of the stove, said supports being held in horizontal position by a ring 24 supported in its lowermost position by lugs 25 extending outwardly from the casing 23, said ring 24 being movable vertically from alignment with the supports 21 when it is desired to collapse said supports for packing the stove when not in use, openings 23a being provided in the casing 23 in alignment with the lower arms of the supports 21 and also with corresponding openings 19a and 19b in the burner housing, to receive said lower arms for the collapsed condition of the supports 21. The ring 15 carries on its upper end a priming cup 26, and the ring 17 is provided with a passageway 17a through which liquid fuel may flow downwardly from above the ring 17 into the cup 26 for starting the stove, the discharge of fuel from the nozzle 16 at that time being in liquid condition because of the cold condition of the stove, and the fuel jet delivered from the nozzle striking the baffle 20 will drop to the lower part of the burner housing and into the upper end of the ring 17.

The lower portion of the valve housing 12 is provided with a vertical axial bore 27 which is threaded at its lower portion to engage corresponding threads on the upper end of a tube 28

extending downwardly in the reservoir 10 to nearly the bottom thereof, said tube 28 being open and free from restriction throughout its entire length. The valve housing 12 has extending radially therefrom a first extension 29 containing internal threads to engage corresponding threads on a valve stem 30, which stem is horizontally disposed and provided at its inner end with a valve member 31 for opening and closing the outer end of a horizontal passageway 32 communicating with the bore 27. The valve housing is recessed at 33 around the valve member 31, and from said recess an oblique passageway 34 extends upwardly and towards the axis of the valve housing and opens in a horizontal slot 35 in the upper end of the valve housing. The slot 35 contains an arm 36a of a sliding block 36 which arm as more clearly shown in Fig. 3, extends laterally from the upper end of the body portion of the block 36 somewhat beyond the axis of the valve housing 12, the vertical body portion of the block 36 being mounted for sliding movement in a vertical slot 37 in the valve housing, which vertical slot is spaced radially from and free from communication with the bore 27 in the valve housing, the vertical slot 37 being displaced angularly from the housing extension 29 by a suitable amount, for example 90°. The valve housing 12 is provided with a second radial extension 38 to support a ball 39 through which the end portion of an operating rod 40 extends, the rod 40 being continued beyond the ball 39 so that its extreme end portion is contained in a recess 36b in the block 36 in such a manner that rotating the ball 39 by vertical movement of the arm 36a, will raise or lower the block 36. The rod 40 is retained in the ball 39 by a suitable collar 40a in any convenient manner, to prevent removal of the rod from the ball. The ball 39 is supported in the housing extension 38 by an internally threaded ring 41 screwed on the outer end of said extension, and by suitable packing material 42 pressed against said ball by said threaded ring. The outer end of the rod 40 is provided with a knob 43 by which the rod 40 may be conveniently actuated to in turn move the block 36 vertically. The arm 36a of the block 36 is internally threaded to engage corresponding threads on the lower end of a vertically extending rod 44 which, as shown in Fig. 1, extends upwardly through the screen material 14a and carries at its upper end a vertically extending needle 44a for movement into the aperture 16a of the nozzle 16 when the block 36 is raised by the operating rod 40.

As a result of the construction described, and as more clearly shown in Fig. 2, it will appear that the mounting devices for the operating rod 40 and the valve stem 30 are in substantially the same horizontal plane, as a result of which no additional vertical height is required in the stove structure as a whole, by the independently actuated nozzle-cleaning mechanism described.

The valve stem 30 is engaged by suitable packing material 45 held in place by an internally threaded ring 46 screwed on the outer end of the housing extension 29, and at its outer end said valve stem has secured thereto an operating disc or handle 47 by which the valve stem may be rotated to control the flow of fuel from the reservoir 10 to the generator 14.

The reservoir 10 is preferably provided with an air pump 48 of any well known construction by which desired air pressure may be produced in the reservoir 10 above the liquid fuel therein, the connection of the pump to the reservoir being prefer-

ably of a kind permitting the ready removal of the pump so that the pump connection with the reservoir may also serve as a fuel-filling opening for the reservoir. The arm 36a of the block 36 loosely fits the horizontal slot 35, so that fuel introduced into the lower portion of the slot 35 through the passageway 34 will readily flow around said arm 36a and upwardly into the lower end of the generator 14.

While I have shown my invention in the particular embodiment above described, I do not limit myself thereto, as I may employ equivalents thereof without departing from the scope of the appended claims.

Having thus described my invention, what I claim is:

1. For use with a liquid fuel burning stove of the class described, controlling mechanism including in combination a valve housing having a fuel passage extending vertically therethrough from the lower end of said housing to the upper end thereof, a valve stem between the upper and lower ends of said housing and in threaded engagement therewith and extending horizontally therefrom and having at its inner portion a valve member for opening and closing said passage, said housing having therein a vertically extending slot spaced horizontally and separate from said passage and also from said valve stem, a block movable vertically in said slot and including at its upper portion an arm extending horizontally towards the vertical axis of said housing, said vertically extending slot having at its upper portion a horizontally continuing slot extending towards the vertical axis of said housing and loosely containing and guiding said arm, a nozzle-cleaning rod secured to and extending upwardly from said arm, and a vertically movable operating rod supported between the upper and lower ends of said housing and operatively engaging said block, whereby movement of said operating rod imparts vertical movement to said cleaning rod, said valve housing having at its upper and lower ends respectively generator-connection means and reservoir-connection means and having an over-all height that is the minimum required to house said valve stem and to carry both of said connection means.

2. For use with a liquid fuel burning stove of the class described, controlling mechanism including in combination a valve housing having a fuel passage extending vertically therethrough from the lower end of said housing to the upper end thereof, a valve stem between the upper and lower ends of said housing and in threaded engagement therewith and extending horizontally therefrom and having at its inner portion a valve member for opening and closing said passage, said housing having therein a vertically extending slot spaced horizontally and separate from said passage and also from said valve stem, a block movable vertically in said slot and including at its upper portion an arm extending horizontally towards the vertical axis of said housing, said vertically extending slot having at its upper portion a horizontally continuing slot extending towards the vertical axis of said housing and loosely containing and guiding said arm, a nozzle-cleaning rod secured to and extending upwardly from said arm, and a vertically movable operating rod supported between the upper and lower ends of said housing and operatively engaging said block, whereby movement of said operating rod imparts vertical movement to said cleaning rod, said hous-

ing including spaced radial extensions in substantially the same horizontal plane respectively supporting said valve stem and said operating rod, said valve housing having at its upper and lower ends respectively generator-connection means and reservoir-connection means and having an over-all height that is the minimum required to house said valve stem and to carry both of said connection means.

3. For use with a liquid fuel burning stove of the class described, controlling mechanism including in combination a valve housing having a fuel passage extending vertically therethrough from the lower end of said housing to the upper end thereof, a valve stem between the upper and lower ends of said housing and in threaded engagement therewith and extending horizontally therefrom and having at its inner portion a valve member for opening and closing said passage, said housing having therein a vertically extending slot spaced horizontally and separate from said passage and also from said valve stem, a block movable vertically in said slot and including at its upper portion an arm extending horizontally towards the vertical axis of said housing, said vertically extending slot having at its upper portion a horizontally continuing slot extending towards the vertical axis of said housing and loosely containing and guiding said arm, a nozzle-cleaning rod secured to and extending upwardly from said arm, a vertically movable operating rod supported between the upper and lower ends of said housing and operatively engaging said block, whereby movement of said operating rod imparts vertical movement to said cleaning rod, and a bearing ball supported by said housing for angular movement and having a bore through which said operating rod extends, whereby vertical movement of the outer end of said operating rod imparts vertical movement in the reverse direction to said cleaning rod, said valve housing having at its upper and lower ends respectively generator-connection means and reservoir-connection means and having an over-all height that is the minimum required to house said valve stem and to carry both of said connection means.

4. For use with a liquid fuel burner of the class described, controlling mechanism including in combination a valve housing having a fuel passage extending vertically therethrough from the lower end of said housing to the upper end thereof, a valve stem extending horizontally from said housing between the upper and lower ends thereof and in threaded engagement therewith and having at its inner portion a valve member for opening and closing said passage, said housing having therein a vertically extending slot spaced horizontally and separate from said passage and also from said valve stem, a block movable vertically in said slot, a nozzle-cleaning rod secured to and extending upwardly from said block, and a vertically movable operating rod supported between the upper and lower ends of said housing and operatively engaging said block, whereby movement of said operating rod imparts vertical movement to said cleaning rod, said valve stem and said operating rod being horizontally displaced from each other, said valve housing having at its upper and lower ends respectively generator-connection means and reservoir-connection means and having an over-all height that is the minimum required to house said valve stem and to carry both of said connection means.

5. For use with a liquid fuel burner of the class

described, controlling mechanism including in combination a valve housing having a fuel passage extending vertically therethrough from the lower end of said housing to the upper end thereof, a valve stem extending horizontally from said housing between the upper and lower ends thereof and in threaded engagement therewith and having at its inner portion a valve member for opening and closing said passage, said housing having therein a vertically extending slot spaced horizontally and separate from said passage and also from said valve stem, a block movable vertically in said slot, a nozzle-cleaning rod secured to and extending upwardly from said block, and a vertically movable operating rod supported between the upper and lower ends of said housing and operatively engaging said block, whereby movement of said operating rod imparts vertical movement to said cleaning rod, said valve stem and said operating rod being horizontally displaced from each other and located in substantially the same horizontal plane, said valve housing having at its upper and lower ends respectively generator-connection means and reservoir-connection means and having an over-all height that is the minimum required to house said valve stem and to carry both of said connection means.

6. For use with a liquid fuel burner of the class described, controlling mechanism including in combination a valve housing having a fuel passage extending vertically therethrough from the lower end of said housing to the upper end thereof, a valve stem extending horizontally from said housing between the upper and lower ends thereof and in threaded engagement therewith and having at its inner portion a valve member for opening and closing said passage, said housing having therein a vertically extending slot spaced horizontally and separate from said passage and also from said valve stem, a nozzle-cleaning rod secured to and extending upwardly from said block, and a vertically movable operating rod supported between the upper and lower ends of said housing and operatively engaging said block, whereby movement of said operating rod imparts a vertical movement to said cleaning rod, said valve stem and said operating rod being horizontally displaced from each other, said housing including spaced radial extensions in substantially the same horizontal plane respectively supporting said valve stem and said operating rod, said valve housing having at its upper and lower ends respectively generator-connection means and reservoir-connection means and having an over-all height that is the minimum required to house said valve stem and to carry both of said connection means.

7. For use with a liquid fuel burner of the class described, controlling mechanism including in combination a valve housing having a fuel passage extending vertically therethrough from the lower end of said housing to the upper end thereof, a valve stem extending horizontally from said housing between the upper and lower ends thereof and in threaded engagement therewith and having at its inner portion a valve member for opening and closing said passage, said housing having therein a vertically extending slot spaced horizontally and separate from said passage and also from said valve stem, a block movable vertically in said slot, a nozzle-cleaning rod secured to and extending

upwardly from said block, a vertically movable operating rod supported between the upper and lower ends of said housing and operatively engaging said block, whereby movement of said operating rod imparts vertical movement to said cleaning rod, said valve stem and said operating rod being horizontally displaced from each other, and a bearing ball supported by said housing for angular movement and having a bore through which said operating rod extends, whereby vertical movement of the outer end of said operating rod imparts vertical movement in the reverse direction to said cleaning rod, said valve housing having at its upper and lower ends respectively generator-connection means and reservoir-connection means and having an over-all height that is the minimum required to house said valve stem and to carry both of said connection means.

8. For use with a liquid fuel burner of the class described, controlling mechanism including in combination a valve housing having a fuel passage extending vertically therethrough from the lower end of said housing to the upper end thereof, a valve stem extending horizontally from said housing between the upper and lower ends thereof and in threaded engagement therewith and having at its inner portion a valve member for opening and closing said passage, said housing having therein a vertically extending slot spaced horizontally and separate from said passage and also from said valve stem, a block movable vertically in said slot, a nozzle-cleaning rod secured to and extending upwardly from said block, and a vertically movable operating rod supported between the upper and lower ends of said housing and operatively engaging said block, whereby movement of said operating rod imparts vertical movement to said cleaning rod, said valve stem and said operating rod being horizontally displaced from each other, said block including at its upper portion an arm extending towards and across the vertical axis of said housing and connected with said cleaning rod substantially in said vertical axis, said valve housing having at its upper and lower ends respectively generator-connection means and reservoir-connection means and having an over-all height that is the minimum required to house said valve stem and to carry both of said connection means.
